UNITED STATES PATENT OFFICE

LOYAL Y. COCHRAN, OF ALLEGHENY, PENNSYLVANIA, AND WILLIAM J. LINDSAY, OF CLEVELAND, OHIO.

FURNACE FUEL-FEEDER.

* SPECIFICATION forming part of Letters Patent No. 391,301, dated October 16, 1888.

Application filed June 20, 1888. Serial No. 277,631. (No model.)

To all whom it may concern:

Be it known that we, LOYAL Y. COCHRAN, of Allegheny, in the county of Allegheny, State of Pennsylvania, and WILLIAM J. LINDSAY, of Cleveland, in the county of Cuyahoga and State of Ohio, have invented certain new and useful Improvements in Furnace Fuel-Feeders; and we do hereby declare the following to be a full, clear, and exact description of the invention, such as will enable others skilled in the art to which it pertains to make and use the same.

Our invention relates to improvements in furnace fuel-feeders; and it consists in certain features of construction and in combination of parts, hereinafter described, and pointed out in the claims.

In the accompanying drawings, Figure 1 is a view in perspective. Fig. 2 is an enlarged detail, hereinafter described.

A represents a dust and fuel collector, the same being supplied through a tube, A'. The collector has usually a hopper or funnel shaped bottom, A², terminating in a tube, A³, and the latter branches into tubes a and a'. Tube a leads into a receiving and storing room, B, where the surplus shavings are received and stored for the time being until they may be disposed of. Tube a' leads to the furnace or furnaces for supplying the same with fuel. A valve, b, located in the crotch of the pipes controls the distribution of fuel through the respective pipes a and a'. In the upright position of the valve shown in solid lines about an equal quantity of shavings will be discharged through the two pipes. In practice, by manipulating this valve a sufficient quantity of fuel is supplied to the furnace and the balance of the fuel discharges into room B.

Pipe a' may have as many branches as there are furnaces or as there are compartments or fire-boxes to be supplied. In the present instance two such branch pipes, C C, are shown with valve e, for controlling the discharge of these pipes, this valve being substantially the same as the one just described.

Pipes C have hinge-joints C', so that the lower sections thereof may be turned back and up out of the way, as shown at the left hand.

The lower horizontal sections of pipe C connect, 50 respectively, with nozzles D, the latter leading into the respective furnaces.

E is a steam-pipe leading from the boiler, pipe E having branches E', corresponding and connecting with pipe C. The lower sections 55 of pipes E' lead, and discharge into the center of the contiguous pipes C, as shown at e', such discharge being in line with nozzles D.

The dust and shavings in these nozzles are blown into the furnaces by the steam-blast, the 60 latter also causing a suction through pipes C, that draws the shavings along down these pipes. Pipes E' have joints e, the axis of which respectively is coincident with the axis of the hinge of the adjacent pipes C, to which 65 such pipe, E', is attached. The joint in each pipe E' may serve, also, as a valve, and shuts off steam when such pipe is turned back and upward out of the way. There are several varieties of such valves that are well known— 70 for instance, the valve shown in Fig. 2. When the pipe is in its depending position connecting with the nozzle D, the valve is open, admitting a full head of steam into the said nozzle. The steam-blast, by reason of its discharging into the furnace, distributes the fuel 75 and aids combustion, and is in every way advantageous.

With the construction shown, where two or more boilers are employed, any one of the 80 boilers and connected furnaces may be cut out of the fuel distribution by simply turning back the pipes, as aforesaid. Cords F and pulleys f are usually arranged for drawing back and holding the different swinging sections of the 85 fuel-pipe.

In practice it is frequently necessary to make so many elbows in the fuel-pipe that there is difficulty in feeding the fuel through such elbows by ordinary means. In such case we 90 provide nozzles connected with the steam-pipe or with branches thereof, these nozzles being located so as to apply a steam-jet inside the fuel-pipe at either side of the elbow, (see nozzles e' and e''), such steam-jets, of course, 95 discharging in the direction that the fuel is to travel in reaching the furnace. With such arrangement of steam-jets at the corners or el-

bows of the fuel-feed pipe no difficulty is had in conducting fuel—such as dust, shavings, &c.—through these pipes.

What we claim is—

- 5 1. The combination, with fuel-distributing pipes having jointed sections, of jointed steam-pipes connected with such jointed sections of the fuel-pipe, the axes of such joints being coincident, and the steam-pipe discharging into the fuel-distributing pipe, substantially as set forth.
- 10 2. The combination, with fuel-collector, fuel-distributing pipe, and furnace, substantially as indicated, such fuel-distributing pipe having a jointed section, of steam-pipe connected with such jointed section of the fuel-pipe, the axes of such joints being coincident, and the steam-pipe discharging into the fuel-distributing pipe, substantially as set forth.
- 15 3. The combination, with a storing-room, a dust and shavings collector, and two or more

furnaces, of pipes diverging from a common point at the lower end of the collector, one of said pipes leading to the storing-room and the other into jointed fuel-pipes, said pipes leading to furnaces, and steam-pipes connected with such jointed sections of the pipes, the axes of such joints being coincident, and the steam-pipe discharging into the fuel-pipes, substantially as set forth.

25

In testimony whereof we sign this specification, in the presence of two witnesses, respectively this 16th day of April, 1888, and this 21st day of April, 1888.

NIMROD McELWAIN,
SAM'L. G. McALLISTER.

Witnesses to signature of Wm. J. Lindsay:

CHAS. H. DORER,
ALBERT E. LYNCH.

30

It is hereby certified that the name of one of the patentees in Letters Patent No. 391,301, granted October 16, 1888, for an improvement in "Furnace Fuel-Feeders," should have been written and printed *William I. Lindsay* instead of "William J. Lindsay," and that the said Letters Patent should be read with this correction therein that the same may conform to the record of the case in the Patent Office.

Signed, countersigned, and sealed this 18th day of December, A. D. 1888.

[SEAL.]

H. L. MULDROW,
First Assistant Secretary of the Interior.

Countersigned:

BENTON J. HALL,
Commissioner of Patents.
